UNITED STATES PATENT OFFICE.

LESTER SMITH, OF PORT WASHINGTON, WISCONSIN, ASSIGNOR OF ONE-FOURTH TO
DELOS H. SMITH, ONE-FOURTH TO DELIA B. SMITH, AND ONE-FOURTH TO OLIVER
H. SMITH, ALL OF PORT WASHINGTON, WISCONSIN.

SHIPPING CRATE.

Application filed June 27, 1924. Serial No. 722,696.

This invention relates to shipping crates. This invention in general is an improvement over that disclosed in United States Patent 1,482,038, issued to me January 29, 5 1924, and has in general the same objects as those set forth in such patent.

The general objects of this invention are to provide a shipping crate which is adapted to receive articles packed in ice, for instance, or otherwise intended for protection from heat, and to provide a shipping crate which will furnish a large degree of insulation from external heat in a simple and effective manner.

15 Further objects are to provide a composite shipping crate which is so formed that the outside may be readily constructed in the usual or any approved manner, and in which a protecting inner compartment spaced from 20 the outer compartment is provided and is so constructed that none of the parts of the compartment may be lost in storage prior to use, and which is so formed that it may be most cheaply manufactured.

25 An embodiment of the invention is shown in the accompanying drawings, in which:—

Figure 1 is a longitudinal sectional view through the shipping crate as it appears when fully assembled such view corresponding to a section on the line 1—1 of Figure 2.

Figure 2 is a sectional view on the line 2—2 of Figure 1.

Figure 3 is a fragmentary view with the top removed and with a portion of the interior cover broken away.

Figure 4 is a plan view of the interior member.

Figure 5 is a fragmentary view of a modified form.

40 The shipping crate comprises an outer container 1 of wood or other suitable material and of box like construction, such member being provided preferably with handles 2 whereby it may be easily transported.

45 The inner member is formed of fiber board or similar material and comprises a blank, such as shown in extended form in Figure 4. This blank is provided with a bottom panel 3, side panels 4, a top panel 5, and end panels 6. All of these panels are formed as one integral structure and score lines are provided to define the panels and to aid in folding the fiber board. Score

lines 7 extend transversely across the blank 55 between the bottom 3 and the sides 4, and a score line 8 similarly extends transversely across the blank between one of the sides 4 and the top 5. A pair of score lines 9 extend transversely across the inner ends of 60 the sides 6, as shown in Figure 4, and join the score lines 7. Short slits are formed at the extreme ends of the score lines 7 to permit ready folding of the members 6 about the score lines 9. Reinforcing and spacing 65 strips of wood or similar material are provided. As shown in Figure 1, a central line of these strips formed by means of a plurality of members 10 which, when the blank is extended, have their ends arranged in 70 abutting relation, as shown in Figure 4.

The ends of the members 4 and 5 are further provided with strips 11, as shown in Figure 4. Strips 12 are secured to the bottom panel 3 and are set inwardly inside of 75 the score lines 9. The ends 6 are provided with centrally arranged strips 13 and with marginal strips 14. When the crate is to be used, the sides 4 are folded along the line 7 and the end members 6 are folded in- 80 wardly along the ends 9.

It is to be noted that the end members are spaced inwardly from the marginal edges of the side members 4 a material distance, and that the reinforced portions at 85 the margins of the side members 4 abut the reinforced marginal edges of the end members and thus secure a firm construction. The top 5 is folded over along the line 8 and, thereafter, the top 1' of the outer compartment 1 is nailed or otherwise secured in position, thus firmly holding the parts in 90 their assembled relation.

An inspection of Figures 1, 2 and 3 will show the spacing of the walls of the inner 95 container or compartment from the walls of the outer container. This spacing is secured by the reinforcing and spacing strips 10, 11, 12, 13 and 14, as described above.

It is clearly apparent, therefore, that the 100 inner crate member is so formed that none of its parts may be lost as they are all integrally formed from one fiber board member. However, it is to be noted that in place of this integral formation, it is obvious 105 that the walls of the inner container or compartment might be hinged by wire loops or other means to each other, so that the

members would have the same freedom to fold which is provided in the preferred form by the score lines described.

It will be seen that an extremely simple and cheap form of shipping crate has been provided in which an inner compartment is spaced from an outer compartment, and in which all of the members of the inner compartment are retained against accidental loss or displacement.

In the modified form shown in Figure 5, the inner container is composed wholly of fiber board or similar material, as indicated at 15. This fiber board is provided with spacing members 16 formed by crimping portions of the board. These crimps are formed at spaced points and replace the spacing strips in the other form of the invention, and may run both vertically and horizontally.

It will further be seen that this shipping crate may be most cheaply manufactured in a simple and easy manner.

Although the invention has been described in considerable detail, it is to be understood that the invention may be variously embodied and is, therefore, to be limited only as claimed.

I claim:

1. A shipping crate comprising an outer compartment of box-like construction, and an inner compartment formed of a single

blank having a rectangular body portion provided with a plurality of parallel score lines defining bottom, side, end and top 35 walls, said blank having laterally projecting flaps and being provided with score lines adjacent the inner end of said flaps, said last mentioned score lines being inset from the marginal edges of said blank, said end 40 walls being provided with reinforcing spacing strips adjacent their side edges, and said side and top walls being provided with reinforcing spacing strips adjacent their end edges. 45

2. A lining for a shipping crate comprising an integral sheet of material having parallel score lines defining top, bottom and side walls, and having outwardly projecting flaps separated from the body portion by 50 score lines, and reinforcing strips secured to said lining along the marginal edges and central portion, said strips and the sheet of material being free to fold into correct box-like formation or to be extended and stored 55 in a flat condition, certain of said reinforcing strips being located adjacent said score lines to aid in defining the lines along which the fold may be made.

In testimony that I claim the foregoing I 60 have hereunto set my hand at Port Washington, in the county of Ozaukee and State of Wisconsin.

LESTER SMITH.
